United States Patent Office.

JOHN WEICHART, OF SAN FRANCISCO, CALIFORNIA.

Letters Patent No. 72,249, dated December 17, 1867.

IMPROVEMENT IN STRAW-CUTTER.

The Schedule referred to in these Letters Patent and making part of the same.

TO ALL WHOM IT MAY CONCERN:

Be it known that I, JOHN WEICHART, of San Francisco, county of San Francisco, State of California, have invented certain new and useful Improvements in Fibre-Cutting Machines; and I do hereby declare the following description and accompanying drawings are sufficient to enable any person skilled in the art or science to which it most nearly appertains to make and use my said invention or improvement without further invention or experiment.

The nature of my invention is to provide an improved machine for cutting all kinds of fibrous material, but chiefly for cutting tobacco, hay, straw, and corn-stalks, so constructed that it will be self-feeding, and the material be brought under the knife in a compact form. In order to accomplish this, I employ a feed-box of any suitable dimensions, having a square-edged iron or steel cutter-bar placed across the outlet. Above this is another bar, having upright pins surrounded by spiral springs, the pins moving up and down in holes on a cross-plate. A corrugated roller, through which a rod passes, is placed across the machine, back of the knife, having at the end of the roller a toothed wheel, which a cam, placed upon a horizontal shaft, operates for turning the roller. Another cam is placed on the horizontal shaft, which gives a peculiar motion to the knife in its downward stroke.

To more fully describe my invention, reference is had to the accompanying drawings and letters marked thereon, of which—

Figure 1 is a side elevation.

Figure 2 is a top view.

Figure 3 is an end view with knife pressed down over the cutting-bar.

Similar letters indicate like parts in each of the figures.

A may represent a suitable receptacle for most of the articles to be cut, across the cutting-end of which is placed a bevelled bar or plate, *a*, having a square edge, over which the cutting-knife shuts. Above this plate is another plate, *b*, which slides up and down in grooves made in the side of the machine. Two upright pins are attached to the plate, around which spiral springs *c c* are placed, the pins moving in holes in an upper plate, *b'*. Back of these plates is placed a corrugated feed-roller, *B*, operated by a wheel, *C*, on the end of a rod which passes through it. Brackets or arms are attached to the side of the machine, which upholds a horizontal shaft with two cams, one of which, *D*, engages the teeth on *C*, which turns the corrugated feed-roller. The cam *E* is in the form of an ellipse, with edges bevelled, turning inward near the minor axes, so that when the cam presses down the knife it will have a drawing movement and incline to the cutting-plate, instead of being forced away from it, as would be the case if the edges were square. A slight curve is made in the end of the knife-bar, along which the cam moves. The knife-bar *F* is jointed to the lower plate *G* by two arms, *d* and *d'*, the lower arm, or *d'*, having a notch in it, against which one end of a steel spring, *H*, rests, the object of which is to throw back the knife after a downward stroke has been made.

The operation of my machine is as follows, to wit: The material to be cut is fed to the machine after the manner of feeding hay or straw to a common feed-cutter, and is pressed up against the corrugated feed-roller, which carries it under the plate *b*, which presses the fibres down compactly by means of the spiral springs *c c*, so that the knife, which is operated by the elliptical cam, in turning the horizontal shaft, will make a downward stroke. Each of the minor axes of the ellipse presses on the end of the knife-bar, and the stroke is made. The spring *H* will press against the arm *d'* and throw the knife back to its original position. If the friction of the arm *E* be found too great on the knife-bar, friction-rollers may be placed in each end of the ellipse, which will have a tendency to greatly facilitate the turning of the shaft.

By the use of my machine all fibrous material may be cut evenly and truly, with ease and dispatch, and more especially is it recommended to the manufacturers of fine-cut tobacco and snuff.

Having thus described my invention, what I claim, and desire to secure by Letters Patent, is—

1. The manner of operating the feed-roller *B* by the toothed wheel *C* and cam *D*, substantially as and for the purposes described.

2. The cam *E*, in combination with the arms *d d'*, jointed to the knife, and the spring *H*, for throwing it back, substantially as described; and

3. The movable pressure-plate *b*, spiral springs *c c*, so that the material to be cut will be held firmly in place, substantially as described and shown.

In witness whereof, I have hereunto set my hand and seal.

J. WEICHART. [L. S.]
